UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

CRUSHING-MILL.

1,072,058.

Specification of Letters Patent.

Patented Sept. 2, 1913.

Application filed July 9, 1913. Serial No. 778,209.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Crushing-Mills, of which the following is a specification, reference being had therein to the accompanying drawings.

10 This invention relates to that class of crushing mills employing rotary beaters or hammers which coöperate with grates or crushing surfaces in the chambers of the mills. In crushing mills of the class referred 15 to the most efficient operation is secured by such an adjustment of the beaters or hammers as will enable them to run closely adjacent to the grates or crushing surfaces. Owing, however, to the wear of 20 the crushing parts, and more particularly to the wear on the rotary beaters or hammers, it is very desirable that a convenient radial adjustment of the working positions of the rotary beaters or hammers should be 25 provided for, to compensate for wear, and the present invention has for its object to supply this desideratum.

In carrying the present invention into effect the pivot-bars, on which the rotary 30 beaters or hammers are mounted, are so constructed with reference to the rotary carrier for the beaters or hammers that a radial adjustment of the working positions of the said beaters or hammers may be effected by 35 a longitudinal adjustment of the said pivot-bars, this result being preferably effected by providing the said pivot-bars with inclined portions which bear against inclined walls of radial slots formed in flanges on the rotary carrier; and thus by adjusting the 40 pivot-bars longitudinally an in or out radial adjustment of the working positions of the rotary beaters or hammers may be provided for.

45 In the accompanying drawing Figure 1 is a diametric sectional elevation of a rotary carrier embodying the present invention, and showing also the rotary beaters or hammers pivotally connected with said carrier. Fig. 2 is an end view of the same. Fig. 3 is a view similar to Fig. 1 but showing a slightly different form of the invention from that illustrated in Fig. 1.

50 Referring to the drawing, 12 denotes a rotary mill shaft and 13 a rotary carrier

splined or otherwise suitably secured to said shaft, said carrier comprising flanges 14 provided with radial slots 15. Fitting in the slots 15, and capable of endwise sliding movements therein, are the pivot-bars 16 60 which connect the rotary beaters or hammers 17 with the said rotary carrier. Said pivot-bars 16 are provided with inclined surfaces 18 fitting against corresponding bearing surfaces afforded by the outer walls 65 of the radial slots 15. The hub portion of the carrier 13 is provided with an external screw-threaded part on which is mounted a nut 19 having a vertical flange engaging notches 20 (in the construction shown in 70 Fig. 1) in the pivot-bars 16, so that by turning the said nut the said pivot-bars may be simultaneously adjusted endwise in either direction for the purpose of varying the radial working positions of the said 75 beaters or hammers 17. The adjusting nut 18 is maintained in any desired position by means of a set-screw 21 provided with a lock-nut 22. The pivot-bars 16 are received loosely in openings 23 in the shank portions of the beaters or hammers 18.

From the foregoing it will be understood that a radial adjustment of the working positions of the rotary beaters or hammers may be conveniently and quickly effected 85 simply by turning the nut 19.

In the construction shown in Fig. 3 both ends of the hub portion of the rotary carrier 13 are screw-threaded for the reception of two adjusting nuts 19 which abut against 90 the ends of the pivot-bars 16 and are thus adapted to effect simultaneous longitudinal adjustments of the pivot bars in either direction by slackening one of said nuts away from the ends of said bars and then screwing up the other nut, these nuts 19 being maintained in any desired position of adjustment by the set-screws 21 and lock-nuts 22, as in the construction first described. 95

100 Having thus described my invention I claim and desire to secure by Letters Patent:

1. In a crushing mill, the combination with a rotary carrier having end flanges and an intermediate flange all provided with radial slots, of rotary beaters or hammers, longitudinally adjustable pivot-bars provided with a plurality of inclines arranged to bear against the outer walls of said slots, 110

said pivot-bars serving to connect said beaters or hammers with said carrier, and means for adjusting said pivot-bars longitudinally to vary the radial working positions of said beaters or hammers.

2. In a crushing mill, the combination with a rotary carrier having end flanges and an intermediate flange all provided with radial slots, of rotary beaters or hammers, longitudinally adjustable pivot-bars provided with inclines arranged to bear against the outer walls of said slots, said pivot-bars serving to connect said beaters or hammers with said carrier, and one or more nuts mounted on said carrier, for adjusting said pivot-bars longitudinally to vary the radial working positions of said beaters.
- 10 3. In a crushing mill, the combination with a rotary carrier having end flanges

and an intermediate flange all provided with radial slots, of rotary beaters or hammers, longitudinally adjustable pivot-bars provided with inclines arranged to bear against the outer walls of said slots, said pivot-bars serving to connect said beaters or hammers with said carriers, one or more nuts mounted on said carrier, for adjusting said pivot-bars longitudinally to vary the radial working positions of said beaters, and means for locking said nut or nuts against rotation when adjusted.

In testimony whereof I affix my signature, in presence of two witnesses.

THOMAS JOSEPH STURTEVANT.
